United States Patent Office.

CYRUS H. LATHAM AND GEORGE D. DUDLEY, OF LOWELL, MASSACHUSETTS, AS-SIGNORS TO WOODS, SHERWOOD & LATHAM, OF SAME PLACE.

Design No. 4,619, dated January 31, 1871.

DESIGN FOR A BOTTLE-STAND.

The Schedule referred to in these Letters Patent and making part of the same.

We, CYRUS H. LATHAM and GEORGE D. DUDLEY, of Lowell, in the county of Middlesex and State of Massachusetts, have invented and produced a new and original Design for a Stand or Caster for Holding Bottles, for any and all purposes for which it can be applied, of which the following is a specification.

The nature of our design is fully represented in the accompanying photographic illustration, to which reference is made.

General Description.

The base of the stand is composed of a rectangular frame, D, to which the wires E are secured. The ends of wires E, one of which is fastened to each longer side of the frame, are bent down to form the legs of the stand.

Within the frame D two rings a a are placed, and properly fastened to the sides, to form supports for the bottoms of the bottles; and just above the rings a the larger rings A A are supported by the wires e b, so as to hold the bottles in place.

The handle C is composed of strands of wire, properly twisted and bent, to form the bow of the handle, and then twisted together to form the thick part of

the handle, and afterward separated and twisted into three strands, two of which are bent to form the rings A, and the remaining one forms the brace c.

The ends of the wires from the brace c are secured to the sides of the frame D and rings a, as shown at d d in the illustration.

As thus made the stand is highly ornamental in appearance.

It will be obvious that our stand may be made for bottles of different sizes and purposes, so that it may be used as a holder for various articles; for instance, as a pickle-jar stand, a tumbler-holder, a decanter stand, &c.

In the illustration it is shown as a perfumery-stand, and in all cases it will retain the same general appearance.

We claim as our invention—

The design for a bottle-stand, substantially as shown in the accompanying photographic drawing.

C. H. LATHAM.
GEO. D. DUDLEY.
